UNITED STATES PATENT OFFICE.

JAMES H. O'NEIL, OF CRANSTON, RHODE ISLAND.

DESIGN FOR AN EMBLEM.

40,561.

Specification for Design.

Patented Mar. 8, 1910.

Application filed January 13, 1910. Serial No. 537,978. Term of patent 7 years.

To all whom it may concern:

Be it known that I, JAMES H. O'NEIL, a citizen of the United States, residing at Cranston, in the county of Providence and State of Rhode Island, have invented a certain new, original, and ornamental Design for an Emblem, of which the following is a specification.

In the accompanying drawings which form a part of this specification, the figure is a front view of an emblem showing my new design.

I claim:

The ornamental design for an emblem, as shown.

JAMES H. O'NEIL.

Witnesses:

HORATIO E. BELLOW,
GEORGE N. McLAUGHLIN.
